The ornamental design for facing for a binder or portfolio, as shown and described.

DESCRIPTION

FIG. 1 is an exterior view of a facing for a binder or portfolio embodying my new design;

FIG. 2 is an exterior view of a facing for a binder or portfolio embodying a variation of my new design; and,

FIG. 3 is a partial cross-sectional view of the facing for a binder or portfolio of FIG. 1 or FIG. 2 taken along line 3—3. The broken line showing of a binder in FIGS. 1-3 is for illustrative purposes only and forms no part of the claimed design.
